US00D790518S

(12) **United States Design Patent** (10) **Patent No.:** **US D790,518 S**
(45) **Date of Patent:** **** Jun. 27, 2017**

(54) **ELECTRONIC DEVICE**

(71) Applicant: **Samsung Electronics Co., Ltd.**, Suwon-si (KR)

(72) Inventor: **Sang Sik Park**, Seoul (KR)

(73) Assignee: **SAMSUNG ELECTRONICS CO., LTD.**, Suwon-si (KR)

(**) Term: **15 Years**

(21) Appl. No.: **29/532,350**

(22) Filed: **Jul. 6, 2015**

(30) **Foreign Application Priority Data**

Jan. 6, 2015 (KR) 30-2015-0000484

(51) **LOC (10) Cl.** **14-03**

(52) **U.S. Cl.**

USPC **D14/248**

(58) **Field of Classification Search**

USPC .... D14/138 AA, 138 AB, 138 AC, D14/138 C, 138 G, 138 R, 248, 250, 253, D14/341, 440; D3/215, 218, 269

CPC H05K 5/0217; H04M 1/03; H04B 1/388; H04N 5/2252; A45C 2011/002

See application file for complete search history.

(74) *Attorney, Agent, or Firm* — McAndrews Held & Malloy, Ltd.

(57) **CLAIM**

The ornamental design for an electronic device, as shown and described.

DESCRIPTION

FIG. 1 is a front perspective view of an electronic device showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a rear perspective view thereof.

The dashed broken lines represent environment and form no part of the claimed design.

1 Claim, 6 Drawing Sheets
